(57) **CLAIM**

The ornamental design for a rectangular push button, as shown and described.

DESCRIPTION

FIG. 1 is a perspective view of the square embodiment of the rectangular push button, which is the subject of the present design;

FIG. 2 is a bottom plan view thereof;

FIG. 3 is a left side elevational view thereof, the right side elevational view being a mirror image thereof;

FIG. 4 is a front elevational view thereof, the rear elevational view being a mirror image thereof;

FIG. 5 is a top plan view thereof;

FIG. 6 is a perspective view of the large square embodiment of the rectangular push button, which is the subject of the present design;

FIG. 7 is a bottom plan view thereof;

FIG. 8 is a left side elevational view thereof, the right side elevational view being a mirror image thereof;

FIG. 9 is a front elevational view thereof, the rear elevational view being a mirror image thereof;

FIG. 10 is a top plan view thereof;

FIG. 11 is a perspective view of the rectangular embodiment of the rectangular push button, which is the subject of the present design;

FIG. 12 is a bottom plan view thereof;

FIG. 13 is a left side elevational view thereof, the right side elevational view being a mirror image thereof;

FIG. 14 is a front elevational view thereof, the rear elevational view being a mirror image thereof;

FIG. 15 is a top plan view thereof;

FIG. 16 is a perspective view of the large rectangular embodiment of the rectangular push button, which is the subject of the present design;

FIG. 17 is a bottom plan view thereof;

FIG. 18 is a left side elevational view thereof, the right side elevational view being a mirror image thereof;

FIG. 19 is a front elevational view thereof, the rear elevational view being a mirror image thereof; and,

FIG. 20 is a top plan view thereof.
